DESIGN FOR A JAR

Willis Burton Adams, Chicago, Ill., assignor to Lysle E. Adams, as trustee

Application March 17, 1937, Serial No. 68,223

Term of patent 3½ years

To all whom it may concern:

Be it known that I, Willis Burton Adams, a citizen of the United States, residing at Chicago, in the county of Cook and State of Illinois, have invented a new, original, and ornamental Design for a Jar, of which the following is a specification, reference being had to the accompanying drawing, forming part thereof and wherein

Fig. 1 is a front elevation of a jar showing my new design;

Fig. 2 is a side view of the jar shown in Fig. 1; and

Fig. 3 is a top plan view of the jar shown in Figs. 1 and 2.

I claim:

The ornamental design for a jar, as shown.

WILLIS BURTON ADAMS.
